UNITED STATES PATENT OFFICE.

FRANK W. HOWSON, OF WASHINGTON, DISTRICT OF COLUMBIA.

GAS-CHECK.

SPECIFICATION forming part of Letters Patent No. 735,101, dated August 4, 1903.

Application filed February 3, 1903. Serial No. 141,658. (No model.)

To all whom it may concern:

Be it known that I, FRANK W. HOWSON, a citizen of the United States, and a resident of Washington, in the District of Columbia, have 5 invented certain new and useful Improvements in Gas-Checks, of which the following is a specification.

My invention relates to improvements in gas-checks for breech-loading guns of that 10 general type known as the "De Bange," in which a plastic pad compressible transversely and expandable radially under pressure of an obturator-head is employed.

The primary object of my invention is to 15 provide a construction which will operate efficiently to close the breech of the gun against the escape of gases formed by the explosive, which will permit of the free manipulation of the breech plug or block in inserting and re- 20 moving the same, which will shield the compressible pad from the gases, and which will further protect said pad from all wear incident to the removal and displacement of the block.

25 Other objects of the invention will appear and the many advantages thereof be appreciated when my novel construction is more fully disclosed.

To effect the ends sought, the invention in- 30 cludes the construction and arrangement of the component parts to be hereinafter described, and particularly set forth in the claims.

While the invention is susceptible of some 35 modification, I have illustrated in the accompanying drawings and shall hereinafter describe in connection therewith what is now conceived to be the preferred embodiment of the same.

40 In the drawings, Figure 1 is a detail transverse sectional view of the breech end of a gun embodying my invention, and Fig. 2 is a perspective view of the metallic packing device. Fig. 3 is a detail sectional view.

45 Prior to my invention certain gas-checks have been constructed designed in part to afford protection to the compressible pad from the gas and flame generated by the explosive, the most common form of which includes re- 50 silient rings mounted at either side of the outer edge of the pad. In this construction the periphery of the pad is arranged, when

the charge is fired and the obturator forced rearwardly, compressing the pad transversely, to make firm contact with the gas-check seat 55 to prevent the gases escaping through the breech of the gun, while the ring referred to, arranged at the front of the pad, is designed to make joint with the wall of the powder-chamber or gas-check seat to support the edge 60 of the pad and prevent exudation of the plastic material of which the same is formed under the enormous pressure placed upon said pad, and said ring acts, further, to an extent as a check to prevent the passage of the gases to 65 said pad. These rings, whether split or made endless and of expandible metal, are not de- 70 signed, nor will they entirely prevent, the escape of gases from the powder-chamber through the breech of the gun, and as a con- 75 sequence the pads must be so constructed and arranged that their peripheries will make contact with the gas-check seat and perform themselves this office. The pad is thus sub- 80 jected to an extent to the action of the 7: gases formed by the explosive, and they are further subjected to attrition caused by con- 85 tact with the wall of the powder-chamber in- 8: cident to the insertion and removal of the breech-block.

It is my purpose to provide a construction in which the pad will be removed entirely from the escaping gases, and the check for preventing the escape of the latter through the breech will be formed entirely by a me- 90 tallic device, the pad itself not being em- 9: ployed to make contact with the gas-check seat, but merely to act upon said metallic joint-closure. The invention includes gen- 95 erally a pad of the character described of much less diameter than the gas-check seat, having a peripheral portion arranged substan- 9: tially parallel to the latter, and pressure-sur- 10: faces extending beyond said peripheral por- 11: tion and forming therewith an annular chan- 11: nel, and a metallic packing arranged in said channel and designed to be pressed into firm contact with the gas-check seat by the pad and said pressure-surfaces when the pad is compressed transversely and expanded ra- 11: dially under the pressure of the obturator- 11: head.

In the accompanying drawings the breech 11: end of the gun or jacket is designated by the

letter *a* and the breech-block fitted thereto by the letter *b*. The obturator, carried by the block, includes the ordinary head *c*, having a substantially flat rear face, between which and the oppositely-arranged front face of the breech-block the compressible and expandable pad *d* is arranged, the same surrounding and being fitted upon the obturator-spindle *e*, which is guided through an axial opening *f* in the breech-block.

Mounted at either side of the outer edge of the pad *d* are two metallic rings *f g*, having flat outer faces arranged coincident with the contiguous flat faces of the pad, inclined faces *h* abutting against contiguous beveled edges of the pad, and second inclined faces *i* extending outwardly beyond the peripheral portion of the pad, between which faces *i* and the faces *h* shoulders *k* are arranged, the latter, together with the faces *i* and the peripheral portion of the pad, forming an annular channel designed to receive the packing device, to be hereinafter described.

The pad *d* is made much smaller in diameter than the powder-chamber or gas-check seat and is provided with a peripheral pressing portion arranged substantially parallel with said seat and substantially in alinement or coincident with the faces of the shoulders *k*.

The packing device, which is located in the channel before referred to, is expandable circumferentially or radially, is provided with an internal face designed to receive the pressure of the peripheral portion of the pad, inclined side walls designed to receive the pressure of the surfaces *i*, and a flat outer peripheral face designed to make firm contact with the gas-check seat. This device is preferably constituted of two sets of expandable rings. One set of said rings comprises two members *m m*, substantially triangular in cross-section, portions of the bases of which find seats upon the shoulders *kk*. Said members have straight inner walls *n*, which are normally separated a slight distance from each other, inclined walls *o*, coacting with the inclined faces *i i*, and inclined sides *p*, constituting with each other and the contiguous surfaces *i i* annular contractible channels designed to receive the members constituting the second set of rings. The members *r* of the second set comprise resilient rings triangular in cross-section, the bases of which are presented to the gas-check seat and the inclined sides of which find bearings against the synclinal walls of said channels, before referred to. The rings *r* are constructed to fit easily in the bore of the gun when in their normal positions, so as to permit of the free manipulation of the breech-block. When the gun is fired, the gases formed by the explosive pressing upon the mushroom-head force the same rearwardly with enormous power and compress the plastic pad transversely between the rear face of said head and front face of

the breech-block, causing the pad to expand radially. The flat peripheral portion *d* thereof is forced against the bases of the rings *m*, which serves to expand the latter, causing the inclined sides *p* thereof to press against the coacting sides of the rings *r*, thereby expanding the latter. Simultaneously the rings *f g* are forced toward each other, causing the inclined surfaces *i* thereof to press against the contiguous sides of the outside rings *r*, and thereby assist in expanding the latter. Through this expansion of the rings *r* the bases thereof are firmly pressed against the gas-check seat, and as the abutting faces or walls of the rings *f g m*, and *r* are likewise firmly pressed together the gas formed by the explosive is absolutely prevented from either escaping through to the breech-block or from reaching the pad *d*.

In order to give the rings *m r*, forming the packing, sufficient resiliency, the same may be split, and in the latter event in assembling said rings the meeting edges thereof are arranged out of alinement with one another, so that the escape of the gases through the spaces between the meeting edges thereof will be checked.

From the foregoing it will be appreciated that the pad is not utilized directly to prevent the escape of the gases, but is protected both from said gases and from any wear incident to the manipulation of the breech mechanism, and it will further be appreciated that the particular construction illustrated in the accompanying drawings and hereinbefore described can be modified or changed within a wide range without departing from the spirit of my invention.

Having thus described my invention, what is claimed as new, and desired to be secured by Letters Patent, is—

1. The combination with a gun-barrel, a breech-block, and an obturator-head, of a pad interposed between said block and head, having a peripheral portion of less diameter than the bore of the gun contiguous thereto and coacting with the walls of said bore to provide a chamber, and a metallic packing including a plurality of expandable rings arranged in said chamber, substantially as described.

2. The combination with a gun-barrel, a breech-block, and an obturator-head, of a pad interposed between said block and head, having a peripheral portion of less diameter than the bore of the gun contiguous thereto and coacting with the walls of said bore to provide a chamber, and a metallic packing including two sets of expandable rings arranged in said chamber, substantially as described.

3. The combination with a gun-barrel, a breech-block, and an obturator-head, of a pad interposed between said block and head, having a peripheral portion of less diameter than the bore of the gun contiguous thereto and coacting with the walls of said bore to pro-

vide a chamber, and a metallic packing arranged in said chamber, said packing including a set of rings coacting directly with said peripheral portion of the pad and a second set of rings coacting with the contiguous portion of the wall of the bore of the gun or the gas-check seat, substantially as described.

4. The combination with a gun - barrel, a breech-block, and an obturator-head, of a pad interposed between said block and head, having a peripheral portion of less diameter than the bore of the gun contiguous thereto and coacting with the walls of said bore to provide a chamber, and a metallic packing arranged in said chamber, said packing including a set of rings having surfaces coacting directly with the peripheral portion of the pad, and a second set of rings having surfaces coacting directly with the bore of the gun or the gas-check seat, the rings of each set having other portions coacting with the rings of the other set, whereby the rings of the second set are expanded, substantially as described.

5. The combination with a gun - barrel, a breech-block, and an obturator-head, of a pad interposed between said block and head, having a peripheral portion of less diameter than the bore of the gun contiguous thereto and coacting with the walls of said bore to provide a chamber, and a metallic packing arranged in said chamber, said packing including a pair of rings having flat bases coacting directly with the peripheral portion of the pad, and inclined sides, and a second set of rings having flat bases coacting with the bore of the gun, and inclined sides coacting with said inclined sides of the rings of the first set, substantially as described.

6. The combination with the gun - barrel, breech-block and obturator-head, of a pad interposed between said block and head, means associated therewith to form a peripheral channel, and an expansible packing-ring arranged in said channel, substantially as described.

7. The combination with the gun - barrel, breech-block and obturator-head, of a pad interposed between said block and head, means associated therewith to form a peripheral channel, and an expansible packing-ring arranged in said channel, said ring comprising a plurality of members having independent movement, substantially as described.

8. The combination with a gun - barrel, breech-block and obturator-head, of a radially-expansible device interposed between said block and head providing a plurality of contractible channels, and an expansible ring located in each of said channels, substantially as described.

9. The combination with a gun - barrel, breech-block and obturator-head, of a radially-expansible device interposed between said block and head providing a contractible channel and an expansible ring located in said channel, substantially as described.

10. The combination with a gun-barrel hav-

ing a gas-check seat arranged in the powder-chamber thereof, breech-block and obturator-head, of a radially - expansible and transversely-compressible pad having a peripheral portion, rings mounted one at each side of the outer edge of said pad having portions projecting beyond said peripheral portion of the pad and coacting therewith and the gas- 75 check seat to form an annular chamber, and a metallic packing arranged in the latter, substantially as described.

11. The combination with a gun-barrel having a gas-check seat arranged in the powder-chamber thereof, breech-block and obturator-head, of a radially-expansible and transversely-compressible pad having a peripheral portion, rings mounted one at each side of the outer edge of said pad having portions 85 projecting beyond said peripheral portion of the pad and coacting therewith and the gas-check seat to form an annular chamber, and a metallic packing including two sets of rings having relative movement arranged in the 90 latter, substantially as described.

12. The combination with a gun - barrel, breech-block and obturator-head, of a compressible radially-expansible pad interposed between said block and head having a peripheral portion, pressing-surfaces extending beyond said peripheral portion and forming therewith an annular channel, a packing-ring located in said channel having side faces corresponding to and coacting with said pressure-surfaces, and an internal face coacting with said peripheral portion of the pad, substantially as described.

13. The combination with a gun - barrel, breech-block and obturator-head, of a compressible radially-expansible pad interposed between said block and head having a peripheral portion, pressing-surfaces extending beyond said peripheral portion at an obtuse angle to the same and forming therewith an annular channel and a packing-ring located in said channel having side faces corresponding to and coacting with said surfaces, and an internal face coacting with said peripheral portion of the pad, substantially as described.

14. The combination with a gun - barrel, breech-block and obturator-head, of a compressible radially-expansible pad interposed between said block and head having a peripheral portion, rings mounted one at each side 12 of the outer edge of said pad having inclined faces forming with said peripheral portion of the pad, an annular channel, and an annular packing member arranged in said channel, substantially as described.

15. The combination with a gun - barrel, breech-block and obturator-head, of a compressible radially-expansible pad interposed between said block and head having a peripheral portion, rings mounted one at each side 13 of the outer edge of said pad having inclined faces forming with said peripheral portion of the pad, an annular channel, and an annular packing member arranged in said channel,

said member having an internal surface arranged parallel with and designed to receive the pressure of the peripheral portion of the pad, and inclined side walls to receive the pressure of said inclined faces of the rings, substantially as described.

16. The combination with a gun-barrel, breech-block and obturator-head, of movable means located between the same providing an ¹⁰ annular channel having outwardly-flaring inclined pressing side walls, and a packing device located in said channel having correspondingly-inclined walls designed to coact with the inclined side walls of said channel, substantially as described.

17. The combination with a gun-barrel, breech-block and obturator-head, of a radially-expansible pad having a peripheral portion, rings mounted one at either side of the ²⁰ outer edge of said pad having inclined portions projecting beyond the periphery of the pad and forming therewith an annular channel, and a metallic packing arranged in the latter comprising two sets of expansible rings ²⁵ having inclined surfaces coacting with the inclined faces of the edge rings, substantially as described.

18. The combination with a gun-barrel, breech-block and obturator-head, of a radially-expansible pad having a peripheral portion, rings mounted one at either side of the outer edge of said pad having inclined portions projecting beyond the periphery of the pad and forming therewith an annular channel, and a metallic packing arranged in the latter including two sets of rings, the members of one of said sets having surfaces coacting with the pad and other surfaces coacting with each other and said inclined face of ³⁵ the edge rings to provide annular channels, the rings of the other set being arranged in said channels, substantially as described.

19. The combination with a gun-barrel, breech-block and obturator-head, of a radially-expansible pad having a peripheral portion, rings mounted one at either side of the outer edge of said pad having inclined portions projecting beyond the periphery of the pad and forming therewith an annular channel, and a metallic packing arranged therein including two sets of rings the members of one of said sets having surfaces coacting with the pad and other surfaces coacting with each other and said inclined face of the edge rings ⁵ to provide annular channels with synclinal walls, the other set of rings forming said packing being arranged in said channels and

having inclined sides coacting with said synclinal walls, substantially as described.

20. The combination with a gun-barrel, breech-block, obturator-head, and pad having a peripheral portion, of rings mounted one at either side of the outer edge of said pad having inclined surfaces extending beyond said peripheral portion, and shoulders coincident ⁶⁰ with said peripheral portion, and a metallic packing comprising two sets of expansible rings, the members of one set having portions designed to seat upon said shoulders and to receive the direct pressure of the peripheral ⁶⁵ portion of the pad, and the members of the other set having portions coacting directly with the gas-check seat, the members of both of said sets having portions coacting with one another, substantially as described. ⁷⁰

21. The combination with a gun-barrel, breech-block, obturator-head, and pad having a peripheral portion, of rings mounted one at either side of the outer edge of said pad having inclined surfaces extending beyond said ⁸⁰ peripheral portion, and shoulder coincident with said peripheral portion, and a metallic packing comprising two sets of expansible rings, the members of one set being substantially triangular in cross-section with their ⁸⁵ bases seated upon said shoulders and presented to the peripheral portion of the pad, and the sides of said members coacting with each other and the inclined faces of the edge rings to provide channels with synclinal walls, and ⁹⁰ the members of the other set being substantially triangular in cross-section and arranged in said channels with their bases presented to the gas-check seat, and their sides coacting with the synclinal walls of said channels, substantially as described. ⁹⁵

22. The combination with a gun-barrel, breech-block and obturator-head, of a pad interposed between said block and head, means associated therewith to form a channel peripherally of said pad, and an expansible packing member arranged in said channel, said member comprising a plurality of split rings having the meeting ends of the same arranged out of alignment with one another. ¹⁰⁰

In testimony whereof I have hereunto signed my name, in the presence of two attesting witnesses, at Washington, in the District of Columbia, this 2d day of February, 1903.
